UNITED STATES PATENT OFFICE.

DANIEL E. PARIS, OF TROY, NEW YORK.

GRATE FOR COAL-BURNING STOVES.

SPECIFICATION forming part of Letters Patent No. 329,206, dated October 27, 1885.

Application filed December 31, 1884. Serial No. 151,624. (No model.)

To all whom it may concern:

Be it known that I, DANIEL E. PARIS, a citizen of the United States, residing at Troy, Rensselaer county, New York, have invented 5 new and useful Improvements in Grates for Coal-Burning Stoves, of which the following is a specification.

It is the object of my invention to provide a grate for wood and coal burning stoves by 10 which the ashes may be perfectly sifted, and in coal-stoves the slag and clinkers thoroughly removed or the entire contents of the fire-pot dumped, as circumstances may require.

The invention consists in a grate composed 15 of three parallel sections, whereof the central part is capable of rotation and vibration, with a vibrating basket moving over or upon the outer sections and reciprocating at right angles to the axis of the central section, the side 20 of the latter rising as the basket approaches it, whereby the cinders and slag are swept from the side grate-sections, and space given upon each side alternately for their discharge into the ash-pan beneath, the central section 25 being also capable of being completely overturned to break up large adhering masses or cut the bottom out of cinder and slag accumulations which fill the fire-pot.

My invention also consists in novel and simple means for operating the grate, and in the 30 several features of construction and combinations of parts hereinafter fully described, and shown in the accompanying drawings, in which—

35 Figure 1 is a plan view of the fire-pot of a stove containing my invention. Fig. 2 is a horizontal section taken in a plane just above the grate. Fig. 3 is a detail perspective of the basket detached. Fig. 4 is a vertical section 40 taken in a plane passing through one end of the stove just outside the gearing of the grate-sections. Fig. 5 is a detail perspective of a part of one of the outer grate-sections removed from its support. Fig. 6 is a perspective showing 45 one method of operating the grate. Fig. 7 is a similar view showing a modification of the construction shown in Fig. 7.

In the said drawings, the reference-numeral 1 denotes the body of the stove, which may be 50 of any desired form and construction. Within said stove-body, and occupying the upper portion of the same, is the fire-pot 2, beneath

which lies the grate, composed of the three sections 3, 4, and 5. Of these the first and the last named are outer or stationary sections, and each is composed of a longitudinal bar, 6, having grate-bars 7 projecting from each side, those adjacent to the front and rear walls of the stove being the shortest.

At one end of each bar 6 is formed a journal, 8, which engages with a seat, 8^a, in the stove-wall, a lug, 9, being formed upon the extremity of said bearing, which hooks into the aperture 8^a. Upon the opposite side of the bearing 8 is formed a depending lug, 10, 60 which lies against or between one or more bosses, 10^a, cast upon the inner face of the stove 1, whereby the sections 3 and 5 are prevented from rotating. Upon the other end of each bar 6 is formed a plain cylindrical bearing, 11, which is laid in a half-seat, 11^a, cast 65 upon the stove opposite each aperture 8^a.

Near each end of the bar 6, a flange, 12, is cast upon one of the grate-bars 7, rising slightly above said bar upon the side most remote from the end of the section. The purpose of this construction, which is the same in both the outer sections, will be explained hereinafter. The flange 12 crosses the longitudinal bar 6, and is extended upon a broadened flat bar, 12^b, projecting from the outer edge of the bar 6, the end of the flange being curved or carried inward, as shown at 12^a.

The central section, 4, consists of a longitudinal bar, 13, having grate-bars 14 projecting from each side, a connecting-web, 15, being formed between the adjacent bars intermediate of the base and the point. Upon one end the bar 13 has a cylindrical bearing, 16, which lies in the seat 16^a formed in the stove-wall, said bar being prolonged and its end, which projects through the wall of the stove, squared to receive a crank or key. The other end of the bar lies in a half-seat, 17, similar to those which support the corresponding ends of the 90 outer sections.

Adjacent to each bearing is formed a segment-gear, 18, projecting upward from the bar 13, for a purpose presently to be described.

Upon the outer sections, 3 and 5, is supported a basket, 19, consisting of an inwardly-inclined oval plate, 20, having a horizontal flange, 21, upon its longer sides, or, in other words, upon those sides which overlie the

outer grate-sections. Upon its lower edge the rear portion of the plate 20 is provided with short teeth 22, those upon the front and end portions being preferably of greater length, 5 as shown at 22^a. Near each end of the front and rear portions of said basket one of these teeth is prolonged somewhat, and its point rests and moves upon the flanged bar near the end of each stationary grate-section, being 10 guided in its movement by the flange 12. Upon each end portion of the basket is cast a rack, 23, which meshes with the segment-gears 18 upon the rotary grate-section. The basket 19 lies intermediate of the grate and 15 the fire-pot, although it in reality forms the lower portion of the latter. The fire-pot, which is composed of sections 24 of corrugated metallic lining or of fire-brick, is supported in any suitable manner whereby the movement 20 of the basket will not be obstructed.

When the parts thus described are properly arranged with relation to each other, the several grate-sections will form the floor of the fire-chamber, the interval between the bars of 25 the inner and those of the outer sections being only sufficient to permit the rotation of the former. The teeth upon the basket will overhang the outer sections and lie in close proximity to their surfaces, while the gears 18 and the 30 racks with which they mesh will be protected from clogging by the overhanging ends of the basket 19 and of the fire-pot.

The operation of these parts is as follows: By applying a key or crank to the projecting 35 squared end of the axial bar 13 in the central section a greater or less rotary movement may be imparted thereto, from a slight vibratory motion or shaking to a complete overturning or semi-revolution thereof. Each 40 movement of the central section is accompanied by a corresponding horizontal reciprocation of the basket 19, which is limited in its movement by the curved extremities 12^a of the flanges 12, and which is caused to move 45 toward the central rotary section as the adjacent edge of the latter rises and forms an opening between it and the outer section, through which the cinders and other refuse are pushed by the advancing teeth of the basket, which 50 sweep over the surface of the outer sections. This reciprocation of the basket not only serves to disintegrate accumulations which become packed in the lower part of the fire-pot, but 55 co-operates with the other parts to form a perfect ash-sifter, thereby avoiding the necessity of removing the mingled coal, cinders, and ashes and sifting them by a separate apparatus.

If large clinkers are found in the fire-pot, 60 they may be easily and quickly broken up by the rotary section of the grate, and when it is necessary to dump the contents of the fire-pot the central section may be turned completely over, cutting the bottom out of the 65 superincumbent mass and bringing the contents of the fire-pot down within the basket and upon the grate.

In operating the central or rotary section of the grate, an ordinary key or crank may be used of the kind shown in the drawings. I 70 propose, however, to operate the grate and vibrate the basket by the following means: In Figs. 6 and 7 the numeral 26 denotes the body of the stove, which is shown as being cylindrical, but which may be of any form. The 75 grate-sections are constructed and arranged in these stoves in substantially the manner heretofore described. Both ends of the longitudinal bar 13, which supports the central section, are prolonged to extend through the opposite 80 walls of the stove, and upon these projecting ends are mounted downwardly - curved arms 27, the lower ends of which support the foot-rail 28. Upon the outer face of this rail, and at the central portion thereof, is formed a handle, 29. This foot-rail serves as a lever whereby the grate may be operated and the basket vibrated. In Fig. 7 the construction and arrangement of parts is the same, with the exception that the foot-rail 28^a is connected directly to the projecting extremities of the central bar of the rotating section. 85 90

It is evident that the construction of the grate may be considerably varied without departing from my invention. The form of the 95 basket and the manner of supporting it may also be modified, and I do not limit myself to the precise form or arrangement shown and described.

This grate operates upon the lower part of 100 the fire-pot, but far enough up to cut out the slag, cinders, and other accumulation, at the same time making an opening for it to pass down into the ash-chamber. The same movement also causes the grate to act after the manner of a shovel to push the disintegrated matter cut out by the upper portion down through the opening formed alternately upon each side, as shown in dotted lines in Fig. 4. The 105 grate is also a perfect ash-sifter. With other grates the coals are packed together by vibration, thus preventing the free circulation of air, or else they "cut off" the bottom of the fire. Both are objectionable, inasmuch as I want to use one motion when the fire is low 110 and the other when the fire is strong but clogged up at the bottom. In this grate I get the benefit of both. The whole bottom of the fire-pot can be vibrated gently when the fire is low, and thus remove the fine ashes, or, 115 when needed, cut off the whole lower part.

What I claim is—

1. The combination of a fire-pot, a movable grate, a basket above the grate, and a gear-connection between the grate and the basket, 125 substantially as described.

2. The combination of an oscillating grate, a basket above the same, and a gear-connection between the grate and the basket, substantially as described. 130

3. The combination of a grate composed of the outer sections and a central oscillating section, with a basket above the grate, and a gear-connection between the oscillatory grate-

section and the basket, substantially as described.

4. The combination of a fire-pot, a grate beneath the same, and a movable basket having depending teeth bearing directly upon the

5 upper side of the grate for loosely supporting the basket thereon, whereby the basket may be reciprocated in a right line across the grate, substantially as described.

10 5. The combination of a grate composed of two outer stationary sections and a central section provided with a shaft, a gear adjacent to each end of the shaft, and a basket having racks engaging the gears, and provided with

15 a toothed or notched lower edge, substantially as described.

6. The combination, with a fire-pot, of a

grate composed of two outer sections, and a central oscillating section provided with gears, and a basket having a horizontal flange and provided with racks engaging said gears, substantially as described.

7. The combination of a movable grate, a basket above the grate, segmental gears connected with the movable grate, and racks up-
25 on the basket engaging the segmental gears, substantially as described.

In testimony whereof I affix my signature in presence of two witnesses.
